INVENTOR.

Samuel D. Keene

UNITED STATES PATENT OFFICE.

SAMUEL D. KEENE, OF PROVIDENCE, RHODE ISLAND, ASSIGNOR TO THE PROVIDENCE EXTRACTOR COMPANY, OF SOUTHBRIDGE, MASS.

MACHINE FOR OPENING AND CLEANING SPINNERS' STAPLES.

SPECIFICATION forming part of Letters Patent No. 244,394, dated July 19, 1881.

Application filed April 30, 1881. (No model.)

To all whom it may concern:

Be it known that I, SAMUEL D. KEENE, a citizen of the United States, residing at Providence, in the county of Providence and State 5 of Rhode Island, have invented an Improvement in Machines for Opening and Cleaning Spinners' Staples, of which the following is a specification.

My invention relates to the construction and 10 arrangement of a separator to be used in connection with an ordinary machine for opening and cleaning spinners' staples, particularly wool, silk, cotton, or flax fiber; and it consists in combining, with a separator having 15 independently-pivoted bars of a peculiar construction, means for adjusting the same both vertically and laterally, as well as the bars thereof upon their axes, as more fully herein-after described.

20 Figure 1 is a vertical section of my machine, and Fig. 2 is a diagram to illustrate the action of air-currents in my improved device.

In the drawings, Fig. 1, A and B represent 25 feed-rolls, C the feeding table or apron, and D D' the arms of the beater. The above-mentioned parts, viz., the feeding table or apron C, feeding-rolls A B, and the beater D D', are all made and arranged in the usual manner.

My improved separator consists of a grill 30 formed of series of bars K K K, each bar being formed as shown by outline of cross-section most clearly in Fig. 2. The sides *a b* and *a d* of the bars K K K have plane surfaces, while the side *b d* is concaved, as shown more 35 plainly in Fig. 2, and the ends of each of the bars K K K have round bearings *k k*, which pass into the end pieces, H H, Fig. 1, so that each of these bars is adjustable about its axis. Several of the upper bars, K K K, have at-

40 tached to their ends arms M M M, which are pivoted to the link N, which is operated by link N' and lever P, the lever P having its fulcrum at P'. By this device the bars K K K may be adjusted as desired, so that the spaces 45 between them may be wider or narrower; also, the angle of deflection due to their sides may be varied. This effect is accomplished in this wise: The handle of the lever P being pressed down, its opposite end raises the link N' nearly 50 vertically, and this in turn raises the link N,

and this in turn the outer ends of the arms M M M, which in turn move the bars K K K upon their pivots so as to change materially the course of air-currents passing between said bars, as is shown in dotted lines in Fig. 55 2. An opposite movement—to wit, raising the handle of the lever P—produces the opposite movement of the bars K K K, the position of said bars shown in Fig. 1 being the normal or usual position of said bars, requiring changes 60 of position, however, to adapt them to the more perfect treatment of wet or damp fiber, or of long or short staple, or, indeed, in accordance with the humidity of the atmosphere where the machine is in operation. It should 65 be understood, in this connection, that all of the bars K K K above named are in the path of air-currents applied in a well-known manner. With this adjustment of the bars K K K upon their axes it also becomes necessary to 70 adjust the grill as a whole both toward and away from the beater, as well as vertically, or nearly so, toward or away from the feed-rolls, the different conditions of the staple, as regards length, humidity, cleanliness, and the 75 like, requiring different adjustment of the grill with respect to said beater and rolls. To effect this adjustment of the grill the end pieces, H H, are connected to the main frame so as to move freely thereon, and said grill is operated 80 by the levers R R', as will now be explained.

The lever R (shown in dotted lines in Fig. 1) is secured upon the sleeve or outside shaft, V, and the lever R' (also shown in dotted lines in Fig. 1) similarly secured upon the inclosed 85 shaft U. The sleeve or outside shaft passes through clamps W, which are rigidly secured thereon, and are provided with arms w, which are free to slide longitudinally in sleeve T, pivoted to the end pieces, H. The inner shaft, U, 90 has also secured to it arms S, working in proper slots in the outer shaft, V, and to the inner ends of the arms S are pivoted one end of links S', whose other ends are pivoted to the frame-pieces H. Therefore, as will be seen, a 95 movement of the lever R' moves the arms S S', which carry up the sleeves T and raise the separator-frames and their bars vertically, or nearly so. By movement of the lever R the same frame and its bars are moved in and out 100

upon the arc of a circle, the shaft V representing the center of the same. By these means, as will be perceived, the separator-grill as a whole is adjustable vertically, or nearly so, and 5 also laterally, while its separate elements, the bars K K K, have their independent adjustment. It should be understood that this machine may be used with or without a suction-fan, drawing in currents of air between the 10 bars K K K. If used with a suction, the currents of air drawn in are to a certain extent met by the currents of air proceeding from the beater; and there should be such an adjustment of the separator-grill as a whole, or of 15 its bars, or of both, as will preserve such an equilibrium of air-currents between the bars as will permit dirt and other extraneous matter to fall out by momentum and gravity and yet retain the fiber from escape and loss. If 20 no suction is used it will be essential to remove the separator-grill a very considerable distance from the path of the beaters, and to so adjust the bars K K K as to leave but narrow openings between them, as shown by solid 25 lines in Fig. 2. The result will be that the currents of air produced by the beater will be so slight at the openings between the bars that the dirt and other foreign matter will be expelled between the bars by momentum and 30 gravity, while the fiber will not pass through or be lost, as shown by the curved arrows in Fig. 2.

The particular form, arrangement, and function of the bars K K K in the grill may be understood by the following explanation: The 35 bars K K K are hung in such a manner that they are each at the same distance from the

center of the beater-wheel when in the position shown in full lines in Fig. 1. In other words, they are located in the arc of a circle 40 a little outside of the path of the beater. By turning the bars K K K about their bearings k k the openings between the lower point, a, of one and the upper part, b, of the next one may be larger or smaller, to adapt the device 45 to the work to be done and to the varying wind-currents which are flowing in the general line represented by the arrow S², Fig. 2. By making these bars K K K with their outer surface b d concaved I obtain a better result than can 50 be obtained by bars having a plane surface, for the reason that particles of dirt falling in the direction of the arrow X will, upon striking the concaved surface b d, be deflected and sent away at a greater angle with the perpendicular than though they struck upon a plane inclined surface, so that the dirt is sent farther 55 away from the point of greatest wind-pressure, which is near the line a d.

Having fully described my invention, what 60 I desire to claim and secure by Letters Patent is—

The combination, with a separator-grill provided with independently-pivoted bars K K K of the form, in cross-section, of right-angled 65 triangles, with the longest side hollowed out, of mechanism for adjusting the said grill both vertically, or nearly so, and laterally, and also the several bars thereof upon their axes, substantially as described.

SAMUEL D. KEENE.
